UNITED STATES PATENT OFFICE.

LOUIS BLESSING, OF JACKSON, MICHIGAN.

RAILWAY-TIE.

No. 873,292.

Specification of Letters Patent.

Patented Dec. 10, 1907.

Application filed April 20, 1907. Serial No. 369,266.

To all whom it may concern:

Be it known that I, LOUIS BLESSING, a citizen of the United States of America, residing at Jackson, in the county of Jackson 5 and State of Michigan, have invented certain new and useful Improvements in Railway-Ties, of which the following is a specification, reference being had therein to the accompanying drawings.

10 This invention relates to improvements in rail road ties and especially to the class known as the reinforced concrete or cement type, wherein the body of the tie is composed of concrete or like plastic material, 15 molded in and around metallic strengthening members.

An object of the invention is to provide a tie of the type described, in which the metallic strengthening members are so disposed as 20 to best resist fracture against the working strains and stresses.

Another object is to furnish rail seats and fastenings adaptable for both tangent and curve, and reinforceable when the situation 25 requires without alteration or undue multiplying of parts.

This invention consists in the matters hereinafter set forth, and more particularly pointed out in the appended claims.

30 Referring to the drawings, Figure 1 is a view in perspective of portions of rails, and a tie embodying features of the invention, partially broken away to give view of reinforcing members, rail seat and locking bolts. 35 Fig. 2 is a view in longitudinal section through a rail seat, showing the locking bolts and drain. Fig. 3 is a view showing the use of additional locking bolts outside of the body of the tie.

40 The upper face of the tie is provided with recesses 5, near each end of the tie, extending well down into the tie, and having a draining duct 6 leading from the recess bottom through the tie. A rail seat 2 is secured on the face of 45 the tie over each recess and may consist of any suitable design which furnishes depending lateral lugs 3 which are adapted to grip the sides of the tie and so prevent lateral displacement, or may preferably comprise a 50 pair of parallel pieces of inverted channel iron, as herein illustrated, whose flanges grip the sides of the tie and the margins of the recess mouth. A transversely disposed cross-pin 8 is embedded near each end of the tie so 55 as to pass through each aperture near the bottom, its projecting ends being upset for

retaining heads, or else screw-threaded and provided with nuts.

Means for holding the rails in place on the seat comprise a pair of obliquely disposed 60 bolts 9 whose lower ends are formed into hooks 10 adapted to engage the cross-pins 8 within the recess while their upper end portions are provided with washers 11 of any preferred suitable design to engage the rail 65 base, and with lock-nuts 12 suitably screw-threaded thereon to force the washers against the rail. When additional bolts are required, as in curves, switches, cross-overs, and the like, an extra pair as 14, may be 70 hooked over the end portions of the cross-pin which project beyond the tie body, in which case the latter, as above stated, are provided with nuts to retain the parts in place. 75

The body of the tie is reinforced by a plurality of straight pieces of cable 15 embedded near each corner, running from end to end. It is further strengthened between the rail-seat recesses by an outer set of cable loops 16 80 whose upper, central, unbroken portions are convex and whose lower end portions lie straight and overlap each other, the extreme ends being inturned if so desired, and a concentrically disposed inner set of loops 17 85 similarly arranged.

To reinforce the body of the tie around each recess and cross-pin, to prevent fracture or tearing off of the upper face of the tie, a special disposition of cable loops is used. 90 This consists of an outer set of parallel loops 18, whose lower central portions pass under the recess in a pendant or curve, and whose upper end portions are laid horizontally over the cross-pin with the ends in overlapping relation. A series of part or open loops 19, are concentrically disposed within and above this outer set, and below the cross-pin, their ends being inturned to form hooks 20 which aid in retaining them in place. If desired, 100 an auxiliary set of cable part or open loops 21 may be likewise embedded within the others and above the cross-pins. 95

The parts are so disposed that the lateral strains from the rail loads are carried well 105 into the body of the tie, and are distributed therethrough in such manner as to minimize the liability to fracture or cleave on planes parallel to the lines of force. Furthermore, the arrangement of the bolts permits wide, 110 lateral adjustment to accommodate different widths of rails. And the additional rail bolts

necessary on curves and the like; are readily added without change of design. Further, the oblique setting of the rail bolts admits of drawing the rails to accurate gage after the 5 tie is set.

Obviously, the general design may be changed, without departing from the spirit of the invention, and I do not limit myself to any particular form or arrangement of parts 10 save as set forth in the appended claims.

Having thus fully described my invention what I claim is:—

1. A railway tie comprising a molded body of cementitious material provided with embedded reinforcing cable loops and straight cable reinforcing members, recesses in the upper face of the tie near each end thereof, cross-pins extending transversely through the recesses, metal rail seats resting on the 15 tie face and rail bolts detachably engaging the cross-pins extending upwardly past the rail seats, provided with rail-locking members on their outer ends.

2. A railroad tie comprising a molded body 20 of cementitious material, recesses in the upper face, near each end, metal cross-pins passing transversely through the recesses, a series of cable reinforcing loops embedded in the body between the recesses, a series of 25 cable reinforcing loops embedded in the body encircling the cross-pins, metal rail seats secured on the face of the tie and rail bolts detachably engaging the cross-pins, extending 30 upwardly beyond the rail seats, provided 35 with rail clamping members.

3. A railroad tie comprising a molded body of cementitious material, recesses in the upper face near each end, metal cross-pins passing transversely through the recesses, a series 40 of reinforcing cable loops embedded in the body between the recesses, with their upper sides convexly curved and their lower sides straight, a series of reinforcing cable loops embedded in the body encircling the 45 cross-pins with their lower sides downwardly curved, and their upper sides parallel to the upper face of the tie, metal rail seats on the face of the tie and rail bolts detachably engaging the cross-pins extending upwardly beyond the rail seats, provided with rail clamping 50 members.

4. A railroad tie comprising a molded body of cementitious material, recesses in the upper face near each end, metal cross-pins passing 55 transversely through the recesses, a series of reinforcing cable loops embedded in the body between the recesses, an outer set of reinforcing cable loops embedded in the body, encircling each cross-pin with their 60 lower sides downwardly curved and their upper sides straight, similar inner concentric sets of reinforcing loops encircling the cross-pins, some of which have their straight portions cut away between the ends, sets of embedded straight reinforcing cable members 65

extending from end to end outside of the loops, metal rail seats on the upper face of the tie, rail bolts detachably engaging the cross-pins, extending upwardly beyond the rail seats, provided with rail locking mem- 70 bers.

5. A railroad tie comprising a molded body of cementitious material, wedged-shaped recesses on the upper face near each end provided with drain ducts passing down through the tie, metal cross-pins passing transversely 75 through the recesses, a plurality of sets of reinforcing cable loops embedded in the body, part of which encircle the cross-pins, apertured metal rail seats resting on the upper 80 face and rail bolts detachably engaging the cross-pins, extending upwardly beyond the seats, provided with rail clamping members.

6. A railroad tie comprising a molded body of cementitious material, recesses in the upper face near each end, metal cross-pins extending transversely through the recesses, sets of reinforcing cable loops embedded in the body both around and between the cross-pins, metal rail seats resting on the upper 90 face of the tie over each recess, each provided with lateral flanges gripping the sides of the tie and with an aperture mating with the mouth of the recess and rail bolts whose lower ends are adapted to detachably engage 95 the cross-pins, and whose upper ends beyond the rail seat are provided with rail clamping members.

7. A railroad tie comprising a molded body of cementitious material, recesses in the upper faces near each end, metal cross-pins extending transversely through the tie and recesses, sets of reinforcing cable loops embedded in the body both around and between the cross-pins, rail seats resting on the 100 upper face of the tie over the recesses, each consisting of a metal plate provided with depending marginal flanges gripping the sides of the tie, and with a slot mating with the mouth of the recess, rail bolts whose lower 105 ends detachably hook around the cross-pins, and whose upper ends beyond the rail seat are provided with rail clamping members, and means on the outer ends of the cross-pins to secure rail bolts engaging said ends 110 against lateral displacement.

8. A railroad tie comprising a molded body of cementitious material, recesses in the upper faces thereof near each end, provided with draining ducts, metal cross-pins extending transversely through the body and each recess, reinforcing cable loops embedded in the body, arranged in sets both between and around the cross-pins, reinforcing straight pieces of cable embedded in the body 120 outside the said loops, extending from end to end of the body, metal rail seats each consisting of a channel iron whose flanges grip the tie and recess sides, and rail bolts whose lower ends detachably hook around the cross- 125 130

pin and whose upper ends pass by said rail-seats and are provided with rail clamping members.

9. The combination with track rails, of a railroad track tie comprising a body of molded cementitious material provided with recesses beneath each rail, a metal cross-pin extending transversely through each recess parallel approximately to the rail, 5 reinforcing loops of cable embedded in the body both between and around said cross-pins, rail-seats interposed between the rail and the tie, each comprising a channel iron whose down-turned flanges grip the sides of

the tie and recesses, track bolts disposed in pairs whose lower ends detachably engage the cross-pins and whose upper diverging ends extend upwardly through and above the rail seats past the said base flange, and are provided with rail clamping members 20 adapted to grip the rail flange on opposite sides.

In testimony whereof I affix my signature in presence of two witnesses.
